UNITED STATES PATENT OFFICE.

CHARLES H. BUCHANAN, OF PHILADELPHIA, PENNSYLVANIA, ASSIGNOR TO
THE AMERICAN NOVELTY SHOE COMPANY, OF SAME PLACE.

DESIGN FOR A SHOE.

SPECIFICATION forming part of Design No. 16,609, dated April 13, 1886.

Application filed January 2, 1886. Serial No. 187,489. Term of patent 14 years.

To all whom it may concern:

Be it known that I, CHARLES H. BUCHANAN, a citizen of the United States, residing at Philadelphia, in the county of Philadelphia and State of Pennsylvania, have invented a certain new and useful Design for Shoes and Articles of Foot-Wear; and I do hereby declare the following to be a full, clear, and exact description of the invention, reference being had to the accompanying photograph, which forms part of this specification.

My design for a shoe, slipper, gaiter, or like article of foot-wear consists in the configuration or ornamentation of the "upper," or all that portion above the sole, the said configuration or ornamentation consisting of strands or layers of braid or tape having a braid-like appearance, said strands or layers being in the form of rings or a continuous spiral, with the edges of each spiral or ring overlapping the next succeeding spiral or ring, so as to appear as a series of steps or joints which will break the monotony of a plain surface and impart to the article a fanciful and attractive appearance.

In the accompanying photograph, A represents the upper embodying my design, said upper showing a succession of joints or laps produced by overlapping of the strands B B of which said upper is composed. 30

I claim—

The design for an article of foot-wear, consisting of a shoe, slipper, or other like article, the upper of which is ornamented by rows of braid-like material following the contour of 35 the opening in the upper, and arranged in substantially parallel series, with their edges overlapping and presenting a corrugated or ridged surface, substantially as shown and described. 40

In testimony that I claim the foregoing I have hereunto set my hand this 8th day of October, 1885.

CHAS. H. BUCHANAN.
